UNITED STATES PATENT OFFICE.

CLINTON ALVORD, OF WORCESTER, MASSACHUSETTS.

TUFT FRAME FOR TUFTED-PILE FABRIC LOOMS.

Application filed November 24, 1928. Serial No. 321,695.

This invention relates to the tuft frames employed in looms for weaving tufted pile fabric such as Axminster carpets. Such frames are suspended on a carrier, by means 5 of which at the required time and in accordance with the desired pattern they are successively presented to the tuft-forming mechanism of the loom. Each frame supports one or more spools containing wound thereon the 10 strands of tuft yarn and is provided with devices for spacing the several yarn strands and presenting them in position to be taken by the tuft-forming mechanism. The latter mechanism usually comprises a series of grippers, one pair for each yarn strand, and consequently the spacing and presenting means is arranged to present the several yarn strands to the grippers. These grippers, after seizing the yarn strands, draw off from 15 the spools the length required to form the tufts and then these lengths are severed from the strands.

The present invention has for its chief object to provide in connection with the tuft frame a simple and efficient means for separating and guiding the yarn strands and presenting them to the tuft-forming mechanisms such as the grippers.

The invention has for its further object to 30 provide such a separating and guiding means in which the yarn strands may readily be threaded broadside into the spaced yarn passages and retained therein so positioned as to be accurately and surely seized by the grippers.

The invention has for its further object to 40 provide such a yarn guide as an integral one-piece unit comprising a plurality of the yarn spacing and guiding passages and particularly such a yarn guide formed of a strip of sheet metal punched, crimped and formed into the required shape, thus facilitating manufacture and insuring identity of all the parts which separate and guide the plurality 45 of yarn strands.

The invention has for its further object to provide such a tuft frame in which the yarn spacing and guiding means are readily and accurately positioned throughout, thus insuring uniformity.

These and other objects and features of the invention will appear more fully from the accompanying description and drawings and will be particularly pointed out in the claims.

As the general construction, purpose and use of a tuft frame for a tufted pile fabric

loom are well known and familiar to those skilled in the art, and as the invention relates only to the yarn spacing and guiding features of the tuft frame, it is sufficient here to illustrate and describe one form of such a tuft frame with preferred forms of the invention embodied therein.

In the drawings:

Fig. 1 is a front elevation partially broken away of a tuft frame shown equipped with three yarn carrying spools.

Fig. 2 is a view in vertical cross section taken on the line 2—2 of Fig. 1.

Fig. 3 is a fragmentary perspective view 70 showing a portion of a yarn guide embodying the invention as it appears before and after being crimped or formed into shape and a portion of one of the attaching combs preferably employed.

Fig. 4 is a transverse cross section of a portion of a slightly different form of yarn guide.

Fig. 5 is a perspective view of a portion of a yarn guide such as shown in Fig. 4 as it 80 appears before and after being crimped or formed into shape.

Fig. 6 is a fragmentary top plan view partially in horizontal cross section of a portion of the construction shown in Fig. 1, but on 85 an enlarged scale embodying the invention.

Fig. 7 is a fragmentary perspective view partially broken away of the construction shown in Fig. 1 and looking toward the bottom.

Fig. 8 is a fragmentary detail in front elevation of a slightly different form of yarn guide embodying the invention.

Fig. 9 is a view in side elevation and partially in vertical cross section of the construction shown in Fig. 1 with the end of a pair of grippers shown in position about to seize a yarn strand.

Fig. 10 is a view generally similar to Fig. 9 showing a variation in the means for attaching the yarn guide to the tuft frame.

The tuft frame is shown as comprising a main body bar 1 preferably in the form of a hollow metal beam of rectangular cross section thus presenting with the minimum 105 weight great strength and rigidity. This body bar is provided at its ends with the usual hangers 2 by which the tuft frame is detachably suspended on the usual carrier. Suitable brackets 3 are supported on the body 110 bar and in these brackets are journalled the yarn carrying spools 4 of which there may be

one or more as required by the width of the fabric being woven.

The yarn guide of this invention is secured to the body bar and presents a series of parallel ribs spaced to form the yarn passages, there being one such yarn passage for each strand of yarn delivered from the spools 4. The yarn guide therefore extends substantially the entire length of the body bar 10 and may be made in one or more sections according to the length of the body bar, or as may be desired. Each section of the yarn guide is an integral one-piece structure preferably formed from a strip of suitable sheet metal. Preferably also the strip of sheet metal is punched, bent and crimped into the required shape and held together and secured to the body bar without the use of solder.

The preferred form of construction is 20 shown in Figs. 1, 2, 3, 6, 7 and 9. A strip of sheet metal 5 is punched as shown at the left-hand portion of Fig. 3. A unit section of the strip when thus punched presents a recess 6 extending inward from the front edge of the 25 strip and three tongues 7, 8 and 9. The tongues are bent back during or after the punching operation into the positions illustrated. The tongue 7 is bent against one face of the body of the strip so that it extends well 30 forwardly of the front edge of the strip to form a threading guide projection. The tongue 8 is bent against the same face of the body of the strip to form a spacing tab. The tongue 9 is pressed so as to project from the 35 opposite face of the strip to form a yarn-retaining finger. The strip is then crimped into the shape shown at the right-hand end of Fig. 3 so that each section of the strip between the adjacent recesses 6 forms a double wall 40 rib 10 with the entire series of such double wall ribs standing parallel and equally spaced, thereby forming between them at the front portion of the guide vertical yarn 45 passages 11. Those portions 12 of the metal of the strip at the rear of the recesses 6 form the 50 union between the parallel ribs 10 and thus form top walls spanning each space at the rear of each yarn passage and merging into the side walls of the ribs.

It will thus be seen that the yarn passages 55 are open at the bottom to provide entrances for grippers such as shown at 13 in Fig. 9. A pair of grippers may therefore enter each yarn passage 11 at the bottom to seize and draw down the end of the yarn strand 14. The yarn passages 11 are of such width as to closely fit the grippers and insure the grippers seizing the strands of yarn, each of 60 which is thus held and guided into proper position by its yarn passage.

It will also be seen that the yarn passages are open at the front to provide broadside 65 yarn threading entrances. This is of great importance because it enables each yarn readily to be threaded into the yarn guide. The

operator may take each yarn strand extending from the spools and pass it broadside into the proper threading entrance, or the 70 yarn strands may first be placed in a comb and then all of the yarn strands simultaneously passed broadside into the series of threading entrances, or any other suitable means may be provided for threading the 75 yarn guide. In order to guide and direct the 80 yarns broadside into the several threading 85 passages, the projections 7 are provided and it will be seen that these projections 7 constitute yarn threading guide projections extending forward from and integral with each rib. Consequently as the 90 yarn is brought broadside toward the guide, each pair of the adjacent projections 7 assist in guiding the yarn into the yarn passage. For this purpose the upper edges of the 95 projections 7 are preferably bevelled off, as illustrated. Where there is but a single spool in the tuft frame, or in the case of the central spool where there are a plurality of spools in the tuft frame, the yarn strands 14, as shown at the central spool 4 in Fig. 1, will 100 all run parallel with the heads of the spool and are readily guided between the respective pairs of projections 7 and broadside into the respective yarn passages. But where there are a plurality of spools, as in 105 the case of the three spools shown in Fig. 1, in a tuft frame, the heads of adjacent spools with the interposed bracket take up considerable space so that the yarn strands at the right and left of the center must converge 110 toward the center of the tuft frame. In order to guide such converging yarn strands properly into their respective yarn passages, the 115 yarn guiding projections 7 at the right and left of the central portion of the yarn guide are inclined away from the center to correspond substantially with the direction of the yarn strands leading to the corresponding threading entrances of the yarn passages.

Each projection 7 in the construction thus far described, it will be observed, is struck out from one wall of each rib 10 and extends between the rib walls forward from each rib, thus slightly separating the rib walls. In 120 order to maintain the symmetry and parallelism of the rib walls, the tongues 8 are provided. Each tongue 8 is therefore an integral tab struck out from one wall of each rib and preferably the same wall as that from which the tongue 7 is struck out, but at the rear portion of the wall so that this tongue serves as a spacer extending between the rib walls.

In order to hold the yarn strands within the yarn passages and prevent them from 125 passing out through the threading entrance, retaining fingers are provided, one for each yarn passage, and in the construction thus far described these fingers are formed by the tongues 9. Each tongue 9 is so positioned in the strip that it extends laterally from the 130

rib wall from which it is struck out across the threading entrance and at its tip stands opposite or slightly enters the aperture 15 in the wall of the opposite rib from which the 5 threading guide projection 7 was struck out. Each tongue therefore constitutes a retaining finger integral with the yarn guide which extends laterally from each rib across the threading entrance and cooperates at its tip 10 with an aperture in the opposite wall. Thus, as illustrated at the right-hand side of Fig. 6, the yarn strand 14 is guided in between the projections 7 and passes broadside into the threading entrance around the tip of the 15 retaining finger 9 and behind the retaining finger so that thereafter it cannot pass forwardly out from the yarn passage.

A yarn guide constructed as thus described is readily and accurately formed by suitable 20 punching, bending and crimping operations and presents a series of units of identical shape and position. But there is more or less yield or give to any given length of such a construction and it is desirable that there 25 should be a slight yield, especially to enable the series of pairs of grippers to cooperate with the yarn guide. It is necessary, therefore, that the yarn guide shall be accurately mounted with the yarn passages properly positioned and spaced on the body bar of the tuft frame, and suitable means are therefore provided for that purpose. In the preferred 30 construction illustrated, a straight edge aligning member shown as a metal strip 16 of a thickness substantially equal to the top wall 12 of the yarn guide is secured to the bottom surface 17 of the body bar 1 in such a position that its front straight edge 18 is at a somewhat less distance from the front 35 surface 19 of the body bar than the length of the top wall 12. A comb plate 20 having uniformly spaced teeth 21 is secured at the bottom of the body bar with its teeth extending between the ribs of the yarn guide so 40 as properly to position the yarn guide and at the same time to press the yarn guide against the flat bottom surface 17 of the body bar. This comb 20 and the aligning member 16 may both be rigidly secured in place by 45 long rivets or bolts 22 extending through the body bar. In order further accurately to position the yarn guide and hold it against the straight edge aligning member 16, a second comb 23 having the teeth 24 and of generally similar construction to the comb 20 is 50 secured to the front surface 19 of the body bar with its teeth between the ribs of the yarn guide and bent around beneath the top walls 12 thereof and acting to press the yarn guide 55 against the straight edge 18 of the aligning member 16. A little space or "wind" 25 extends between the comb 23 and the bottom of the front surface of the body bar and the comb 20 is set back so that the top wall cannot 60 abut the base of the teeth. Consequently the

yarn guide may be very tightly clamped and accurately positioned on the body bar. The comb 23 may be secured in place by rivets 26 passing transversely through the body bar.

While the yarn guide must be properly 70 aligned on the body bar, other straight edge aligning means may be employed than the plate 16. As shown, for example, in Fig. 10, the comb 20 may be bolted directly by the bolts 22 to the body bar with its teeth 21 extending between the parallel ribs of the yarn guide and with the base of the comb constituting the straight edge aligning member.

A slightly different form of construction 80 of the yarn guide is shown in Figs. 4 and 5.

In this construction the parallel walls forming the ribs are pressed close together without any spacing tabs, thus enabling wider yarn passages to be secured with sheet metal of a given thickness. In this case the recesses 27 are punched out corresponding to the recesses 6. Between each pair of recesses there is punched out a long tab forming the aperture 28 and in line with this aperture at the front edge is punched out a short recess. 90 The long tab is bent inwardly, as shown at 29, to form the retaining finger and is also bent parallel with the strip and inserted in the recess in line with the aperture 28 to form the required yarn threading guide projection 95 30. But it will be seen that this projection 30 fitting in the recess in line with the aperture 8 lies within the strip so that when the strip is crimped into position, as shown at the right-hand side of Fig. 5, the walls forming 100 the ribs may be pressed tightly together. In each unit section an aperture 31 is punched out to come opposite the retaining finger 29.

Another form of construction for widening the thread passage, especially at the bottom portion constituting the gripper entrance, is indicated in Fig. 8 where the double wall ribs 40 are pressed tightly together at the bottom and are spaced slightly apart at the top. Thus the lower portions 41 of the 105 thread passages are wider than the upper portions and give more room for the operation of the grippers, thus enabling wider grippers to be employed, if desired.

Having thus described the invention, what 115 is claimed as new, and desired to be secured by Letters Patent, is:

1. A yarn guide for a tuft yarn frame comprising a strip of metal transversely crimped to present a series of spaced, parallel, double 120 wall ribs, the opposed rib walls of adjacent rib sections merging at the top of their rear portions leaving the front portions of said ribs separated to form vertical yarn passages presenting at the front broadside threading 125 entrances and the said spaced ribs at the bottom presenting gripper entrances.

2. An integral one-piece yarn guide for a tuft yarn frame comprising a series of parallel, double wall ribs equally spaced to form 130

yarn passages, open at the bottom to provide gripper entrances and open at the front to provide broadside yarn threading entrances and a top wall spanning each space at the rear 5 of each yarn passage and merging into the side walls of the ribs.

3. An integral one-piece yarn guide for a tuft yarn frame comprising the construction defined in claim 2, together with an integral 10 yarn threading guide projection extending forward from each rib.

4. An integral one-piece yarn guide for a tuft yarn frame comprising the construction defined in claim 2, together with an integral 15 yarn threading guide projection extending forward from each rib with the projections at each side of the central section of the guide inclined toward the center to correspond substantially with the direction of the yarn 20 strands leading to the respective threading entrances.

5. An integral one-piece yarn guide for a tuft yarn frame comprising the construction defined in claim 2, together with an integral 25 retaining finger extending laterally from each rib across the threading entrance and cooperating at its tip with the opposite rib to permit the broadside passage of the yarn through the threading entrance and to prevent its 30 withdrawal from the yarn passage through said entrance.

6. An integral one-piece yarn guide for a tuft yarn frame comprising the construction defined in claim 2, together with an integral 35 yarn threading guide projection extending forward from each rib and an integral retaining finger extending laterally from each rib across the threading entrance and cooperating at its tip with the opposite rib to permit the broadside passage of the yarn through 40 the threading entrance and to prevent its withdrawal from the yarn passage through said entrance.

7. An integral one-piece yarn guide for a tuft yarn frame comprising the construction defined in claim 2, together with an integral 45 yarn threading guide projection struck out from one wall of each rib and extending between the rib walls forward from each rib, and an integral retaining finger extending laterally from each rib across the threading entrance and cooperating at its tip with the aperture in the wall of the opposite rib from which the said projection is struck out to permit the broadside passage of the yarn into the 50 yarn passage through the threading entrance and to prevent its withdrawal from the yarn passage through said entrance.

8. An integral one-piece yarn guide for a tuft yarn frame comprising the construction defined in claim 2, together with an integral 55 yarn threading guide projection struck out from one wall of each rib and extending between the rib walls forward from each rib, an integral retaining finger extending lateral-

ly from each rib across the threading entrance and cooperating at its tip with the aperture in the wall of the opposite rib from which the said projection is struck out to permit the broadside passage of the yarn into the yarn 70 passage through the threading entrance and to prevent its withdrawal from the yarn passage through said entrance, and an integral tab struck out from one wall of each rib in the rear portion thereof and extending between the rib walls.

9. A tuft yarn frame having a series of passages to receive yarn and provided with a series of rigid walls forming entrances for grippers spaced uniformly with said yarn 80 passages, each yarn passage being provided with a broadside threading entrance, one of each two adjacent walls forming said broadside threading entrance having an aperture and other of said walls having a finger 85 extending therefrom across the broadside threading entrance with its tip cooperating with said aperture to permit the broadside passage of the yarn into the yarn passage through the threading entrance and to prevent its withdrawal from the yarn passage 90 through said entrance.

10. A tuft yarn frame comprising a body bar presenting a flat bottom surface, a straight edge aligning member upon and extending longitudinally of said bottom surface, a yarn guide presenting a series of parallel ribs spaced to form yarn passages, a comb and means for securing the comb to the front of the body bar with its teeth between the ribs of the yarn guide and acting to press the 100 yarn guide against the straight edge of the aligning member.

11. A tuft yarn frame comprising a body bar presenting a flat bottom surface, a straight edge aligning member upon and extending longitudinally of said bottom surface, a yarn guide presenting a series of parallel ribs spaced to form yarn passages, a comb and means for securing the comb at 110 the bottom of the body bar with its teeth between the ribs of the yarn guide and acting to press the yarn guide against the flat bottom surface of the body bar.

12. A tuft yarn frame comprising a body bar presenting a flat bottom surface, aligning means upon and extending longitudinally of said bottom surface, a yarn guide presenting a series of parallel ribs spaced to form yarn passages, a comb and means for securing the comb to the front of the body bar with its teeth between the ribs of the yarn guide and acting to press the yarn guide against 120 said aligning means.

13. A tuft yarn frame comprising a body 125 bar, a yarn guide presenting a series of parallel ribs spaced to form yarn passages, means on the bottom surface of the body bar extending longitudinally thereof to align the rear edge of the yarn guide and space the ribs 130

thereof and means on the front of the body bar acting to press the yarn guide against said aligning and spacing means.

14. A tuft yarn frame comprising a body bar, a yarn guide presenting a series of parallel ribs spaced to form yarn passages, means on the bottom surface of the body bar extending longitudinally thereof to align the rear edge of the yarn guide, space the ribs there-
10 of and clamp the yarn guide to the body bar and means on the front of the body bar acting to press the yarn guide against said aligning, spacing and clamping means.

15. A tuft yarn frame comprising a body bar presenting a flat bottom surface, a straight edge aligning member upon and ex-

tending longitudinally of said bottom surface, a yarn guide presenting a series of parallel ribs spaced to form yarn passages, a comb and means for securing the comb at the bottom of the body bar with its teeth between the ribs of the yarn guide and acting to press the yarn guide against the flat bottom surface of the body bar, and a second comb and means for securing the second comb to the front of the body bar with its teeth between the ribs of the yarn guide and acting to press the yarn guide against the said aligning member. 20 25

In testimony whereof, I have signed my name to this specification.

CLINTON ALVORD.
